UNITED STATES PATENT OFFICE.

EDWARD I. BRADDOCK, OF WINCHESTER, MASSACHUSETTS, ASSIGNOR TO
HENRY W. LAMB, OF BROOKLINE, MASSACHUSETTS, AND DAVID A.
RITCHIE, OF CAMBRIDGE, MASSACHUSETTS.

MANDREL.

SPECIFICATION forming part of Letters Patent No. 718,082, dated January 13, 1903.

Application filed December 23, 1901. Serial No. 88,873. (No model.)

To all whom it may concern:

Be it known that I, EDWARD I. BRADDOCK, a citizen of the United States, residing in Winchester, in the county of Middlesex and State of Massachusetts, have invented an Improvement in Mandrels, of which the following description, in connection with the accompanying drawings, is a specification, like letters on the drawings representing like parts.

10 This invention relates to a novel mandrel especially designed and adapted for use in the manufacture of composite non-corrodible pipe, substantially such as shown and described in United States Patent No. 610,224, dated September 6, 1898.

In the practical manufacture of non-corrodible pipe such as above referred to it has been ascertained that a mandrel composed wholly of metal, such as iron or steel, is unsuitable, or at least unreliable, for perfect work carried on continuously, or, as it may be termed, in a "practical manner," owing to the fact that the metal mandrel becomes coated by the molten metal, and when the portion of the molten non-corrodible metal within the iron or steel tube and between it and the mandrel is subjected to a chilling action the non-corrodible metal contracts and adheres to the metal mandrel, thereby rendering it difficult to move the mandrel with relation to the iron or steel tube, or vice versa, and the non-corrodible metal adheres so firmly as to tear it away from the portion adhering to the iron or steel tube, thereby reducing the thickness of the non-corrodible tube in the composite pipe and also leaving a roughened surface on the interior of the composite pipe.

The object of this invention is to overcome the objectionable features above referred to, and I accomplish the desired object by the employment of a mandrel provided for substantially the greater portion of its length with a non-metallic surface of a material which is unaffected by the heat of the molten metal and to which the molten metal does not adhere.

The non-metallic material preferred by me and with which I have obtained excellent results is mica, and the desired length of non-

metallic surface I have obtained by assembling mica disks on a metal rod or support and compacting said disks so as to practically form a cylinder or tube of mica, as will be described. These and other features of this invention will be pointed out in the claims at the end of this specification.

Figure 1 is an elevation of a mandrel embodying this invention, and Fig. 2 a longitudinal section on the line 2 2 of the mandrel shown in Fig. 1.

Referring to the drawings, *a* represents a rod or supporting-core for a plurality of disks *b*, which are mounted on the core or rod *a* and are firmly compacted together by means of a head *c* on one end of the rod *a* and a nut *d* on the other end thereof. The disks *b* are composed of a non-metallic substance which is unaffected by molten tin, lead, zinc, or the like employed in the manufacture of the non-corrodible pipe referred to, and the said disks are preferably made of mica. The mica disks *b* are placed on the rod *a* and after being secured firmly in place by the nut *d* may be turned down to the size or diameter desired, so as to form practically a mica cylinder mounted on a metallic core or support and suitably confined in place thereon. The mica cylinder mounted on the rod *a* and the head *c* and nut *d* form a composite mandrel, which in practice may and preferably will be attached to a suitable rod *e*, which may be of any desired length and constitutes a handle for or extension of the mandrel. This attachment may be effected by a centering device, which latter may be of any suitable construction, but preferably that herein shown, it consisting of a plurality of pieces *f g h* of like construction and assembled to form practically a cylinder provided at its opposite ends with internal grooves *i j*, one of said grooves, as *i*, loosely engaging the head *k* of a bolt or threaded rod *l*, attached to the head *c* of the mandrel, and the other of said grooves, as *j*, engaging the head *m* of the rod *e*, to which a collar *n* is attached, as by a pin *o*. (Shown by dotted lines, Fig. 2.)

The head *c* of the mandrel is provided with a recess or socket *p*, into which project fingers *q* on the front ends of the pieces consti-

tuting the centering device. The pieces constituting the centering device are provided at their rear ends with fingers *r*, which extend into pockets *s*, formed in the collar *n*, as by 5 partition-walls *t*.

The groove *i* is provided with a beveled front wall *u*, which co-operates with the head *k* of the bolt or rod *l* to expand the centering device beyond the diameter of the mandrel 10 and sufficient to engage the inner wall of the iron or steel pipe when strain is exerted upon the rod *e*, thereby accurately centering the mandrel within the said pipe and insuring the formation of a non-corrodible tube within 15 the same of substantially uniform thickness.

Instead of the particular form of centering device herein shown other forms may be used.

I may prefer to form the non-metallic surface of the mandrel of mica disks, as herein 20 shown; but I do not desire to restrict my invention in this respect.

I claim—

1. A mandrel for forming composite non-corrodible pipe, comprising a center rod provided at one end with an enlargement or 25 head, a plurality of disks of a material to which molten metal does not adhere and which

is substantially unaffected by the heat of said molten metal, said disks being arranged on the said rod for substantially its length, and 30 a metallic head fitted upon the free end of said rod to press the disks in close contact with one another to form a compact body, and to retain said disks in said compact form, substantially as described. 35

2. A mandrel for forming composite non-corrodible pipe comprising a metallic center piece or rod, a plurality of mica disks mounted upon said rod in contact with one another and for substantially the length of said center piece, and metallic end pieces between 40 which said mica disks are confined to form a compact body, substantially as described.

3. A mandrel composed of metallic portions and a plurality of interposed mica disks, substantially as described. 45

In testimony whereof I have signed my name to this specification in the presence of two subscribing witnesses.

EDWARD I. BRADDOCK.
